UNITED STATES PATENT OFFICE.

SIGMUND L. LEDERER, OF PROVIDENCE, RHODE ISLAND.

DESIGN FOR A BRACELET CHAIN LINK.

Application filed March 17, 1926. Serial No. 16,951. Term of patent 7 years.

To all whom it may concern:

Be it known that I, SIGMUND L. LEDERER, a citizen of the United States, residing at Providence, in the county of Providence and State of Rhode Island, have invented a new, original, and ornamental Design for a Bracelet Chain Link, of which the following is a specification, reference being had to the accompanying drawings, forming part thereof.

I claim:

The ornamental design for a bracelet chain link, as shown.

In testimony whereof I have signed my name to this specification.

SIGMUND L. LEDERER.
